PASQUALE RUGGIERO, OF PHILADELPHIA, PENNSYLVANIA.

HEEL FOR SHOES.

1,227,202.

Specification of Letters Patent. Patented May 22, 1917.

Application filed July 8, 1916. Serial No. 108,087.

To all whom it may concern:

Be it known that I, PASQUALE RUGGIERO, a citizen of the United States, residing at Philadelphia, in the county of Philadelphia and State of Pennsylvania, have invented 5 a certain new and useful Heel for Shoes, of which the following is a specification.

The present invention relates to heels for shoes and other footwear and has for one 10 object to provide a durable and economical heel as a complete article of manufacture which may readily be attached in a permanent manner to the sole of a shoe.

A further object of the invention is to 15 provide a fastening means for heels whereby a heel is united to the shoe sole firmly and effectively for the purpose intended while at the same time providing for replacing worn parts of the heel should wear take 20 place.

A further object is to provide a heel construction particularly adaptable for women's high or French heels so that the life of such heels is not only prolonged but interchangeability is made possible.

For the purpose of illustrating my invention, I have shown in the accompanying drawings one form thereof which is at present preferred by me, since the same has been 30 found in practice to give satisfactory and reliable results, although it is to be understood that the various instrumentalities of which my invention consists can be variously arranged and organized and that my 35 invention is not limited to the precise arrangement and organization of the instrumentalities as herein shown and described.

Figure 1 represents a sectional elevation of a shoe heel and attaching means embodying my invention.

Fig. 2 represents a perspective of one of the heel sections.

Fig. 3 represents a similar view of another heel section;

Fig. 4 represents a perspective of the fastening plate.

Fig. 5 represents a perspective of a washer employed in connection with the clamping means.

Fig. 6 represents in section the heel of a woman's shoe showing my invention.

1 designates the sole of a shoe, the same 55 extending in the usual manner over the heel, so that the latter may be properly fixed to the shoe proper. In the preferred form of my invention, the heel (denoted generally

by 2) is formed of wooden sections or layers 3 and 4, the former having the grain running in a direction parallel to the length of the heel section and the latter having the grain at right angles to the length. In building up the heel these sections are preferably alternately placed so that first there is a section with the grain running in one direction and then a section with the grain running at right angles thereto so that a strong effective heel structure is provided which is capable of resisting breaking or splitting in use. It will of course be understood that I do not wish to be limited to any particular direction of the grain in each layer since this is substantially immaterial as long as the layers are laid alternately with the grain of one crossing the grain of the next.

5 designates an outer or tread section, preferably of leather, though rubber or the like may serve to advantage, said section in the present instance having a substantially centrally disposed depression 6 forming a seat to receive and conceal the washer 7 and its adjuncts.

8 designates a plate provided with an aperture 9 and having a plurality of prongs 10 which are suitably disposed to be driven into the heel part as will be described. The rivet pin 11 is adapted to pass through the aperture 9 and be forcibly driven through the heel sections so that its end may be upset or riveted in the required manner.

It will be understood that the heel sections are nailed together as indicated at 12 to form a complete finished heel ready to be attached to the shoe and in consequence they may be made up in large quantities. The method of attachment consists in placing the heel in position beneath the heel portion of the sole and driving the prongs 10 through the sole 1 and into the heel so that the body of the plate is substantially embedded in the upper face of the sole and lies flush therewith. The rivet pin 11 is then driven through the sole and heel and metal washer 7 placed over its protruding end and that end is then upset or headed over so that the sole, heel and their adjuncts are firmly clamped in place. It will be noted that the plate 8 covers a relatively large area of the heel so that the strains encountered in use are distributed in an effective manner and there is practically no chance for the heel to work loose or become detached. Where high

- heel shoes are used, as the majority of women's shoes are made, the device is particularly applicable since it is well known that the ordinary high or French heel wears quickly on one side or the other and frequently breaks off entirely. Such heels are generally extremely difficult to repair or replace but when the heel is of wood and built up in accordance with my invention, the 10 tendency to wear unevenly is reduced to a minimum and if it should occur a new section may be quickly substituted or the old one removed and the clamping pin further upset to hold the remaining sections in place. 15 Should it be necessary to replace the entire heel it may readily be done by removing the pin 11, placing a new heel in position and again fixing the plate 8 by a newly riveted pin. 20 It will now be apparent that I have devised a complete unitary heel structure of simple construction but effective in operation for the purpose intended and furthermore exceedingly cheap to manufacture. 25 The substitution of wood for leather in the body of the heel contributes to long wearing qualities, economy in production, lightness

as to weight and the complete heel maintains its shape under all normal conditions of wear.

What I claim is:—

In a device of the character stated the combination of a shoe sole, a heel formed of a plurality of sections arranged in superposed relation, the grain of one section being crosswise with respect to the grain of the next section, auxiliary fastening means for holding said sections together to form a complete unitary heel, a plate adapted to seat upon said sole on the opposite side from said heel, said plate having a plurality of prongs adapted to pass through said sole into said heel to prevent relative turning movement, a substantially centrally disposed rivet pin passing through said plate, sole and heel to clamp the parts together and a washer forming a bearing for the upset end of said rivet.

In testimony whereof, I have hereunto signed my name.

PASQUALE RUGGIERO.
